UNITED STATES PATENT OFFICE.

JOHN HAYS HAMMOND, JR., OF GLOUCESTER, MASSACHUSETTS.

TRANSMITTING AND RECEIVING SYSTEM.

Application filed May 13, 1920, Serial No. 381,163. Renewed August 15, 1924.

To all whom it may concern:

Be it known that I, JOHN HAYS HAMMOND, Jr., a citizen of the United States, and a resident of Gloucester, county of Essex, State of Massachusetts, and whose post-office address is Hammond Radio Research Laboratory, Gloucester, Massachusetts, have invented certain new and useful Improvements in Transmitting and Receiving Systems, of which the following is a specification.

One of the objects of the present invention is to provide means for transmitting a series of high frequency waves, for impressing a plurality of series of oscillations of different, secondary frequencies upon said series of waves, and for separately modifying the oscillations. A further object of the invention is to provide means for transmitting a plurality of signals or messages simultaneously and selectively receiving said signals or messages. A still further object of the invention is to provide means for receiving a series of high frequency waves modified at a plurality of secondary frequencies above audibility by series of oscillations, each of which is in turn separately modulated at an audio frequency, and selectively receiving the respective, modulated, secondary frequencies. The invention also aims to provide other improvements as will hereinafter appear.

In the accompanying drawing Fig. 1 represents diagrammatically one form of transmitting system embodying the present invention; and Fig. 2 represents diagrammatically one form of receiving system embodying the present invention.

Referring to Fig. 1 of the drawing, the transmitting system includes an open, aerial circuit 10 having an antenna 11, grounded at 12 and including a secondary coil 13 of a transformer 14.

For impressing high frequency oscillations upon the aerial circuit 10 to produce a high frequency carrier wave, the secondary coil 13 is inductively coupled to an oscillating circuit 15 through a primary coil 16. A condenser 20 is included in the circuit 15, and the latter is connected to a source of current, such as an alternating current generator 21, through suitable inductive resistances 22 and 23.

To impress a secondary frequency or a plurality of secondary frequencies upon the high frequency wave of the aerial circuit 10, a closed circuit 24 is provided which is

grounded at 25 and includes a thermionic valve 26 of any well known form. In the present instance, this valve 26 is of the evacuated glass bulb type having a plate 60 electrode 27 connected to the circuit 10; a grid 28 included in the circuit 24, and a filament 29 also contained in the circuit 24 and heated by a battery 30 in a well known manner. Preferably, the circuit 24 includes 65 a plurality of secondary coils 31 and 32 inductively coupled respectively to two circuits 33 and 34 through primary coils 35 and 36. Suitable sources of high frequency current, such as alternating current generators 70 40 and 41, are respectively included in the circuits 33 and 34 and are arranged to produce oscillations of different, super-audible frequencies in the two circuits. Thus the circuit 33 energized by the generator 40 will 75 impress a series of oscillations of one frequency upon the circuit 24 while the circuit 34 energized by the generator 41 will impress a series of oscillations of a second and different frequency upon the circuit 24. 80

For varying the amplitude of the two impressed series of oscillations two telephone transmitters 42 and 43 are included respectively in the two circuits 33 and 34. Two speakers can simultaneously use the telephones 42 and 43. The vacuum tube 26 is so connected to the antenna that the carrier wave is modulated by the two series of oscillations produced by the high frequency generators 40 and 41 at two super-audible frequencies. On these two series of oscillations there are impressed the individual speech modulations of the two speakers respectively. Thus the energy transmitted from the antenna 11 is modified by the two frequencies produced by the alternators 40 and 41, and these two frequencies in turn are modified in their amplitude by the sound waves actuating the telephone transmitters 42 and 43 in the respective circuits 33 and 34. 95

For receiving messages or signals transmitted by the above-described transmitting system a receiving, open, aerial circuit 50 is provided comprising an antenna 51 grounded at 52 and comprising a primary coil 53 of a transformer 54. The primary coil 53 is inductively coupled to a secondary coil 55 included in a closed, oscillatory circuit 56 tuned to the high frequency of the carrier wave transmitted from the antenna 11 with the alternator 21 as a source. A condenser 57 is also included in the circuit 105 110

56. The oscillatory circuit 56 is connected at one side by means of branch conductors 60 and 61 respectively to grids 63 and 63' respectively of a suitable detector 64 which 5 is here shown as of the evacuated bulb type. The other side of the circuit 56 is connected by a conductor 65 to the filament 66 of the detector 64.

For selecting either of the received, modified, secondary frequencies, or selecting both simultaneously, the branch conductor 60 includes a closed, oscillatory circuit 70 tuned, for example, to the frequency of the oscillations produced by the alternator 40, while the 15 branch conductor 61 includes a closed, oscillatory circuit 71, tuned to the frequency of the oscillations produced by the alternator 41. The circuit 70 includes a condenser 72 and is inductively coupled by a primary coil 73 to a secondary coil 74 included in an oscillatory circuit 75 having a condenser 76 and tuned to the same frequency as the circuit 70. This circuit 75 is arranged in a lead 77 connected to a plate 20 electrode 78 of the detector 64. The circuit 71 includes a condenser 80 and is inductively coupled by a primary coil 81 to a secondary coil 82 included in an oscillatory circuit 83 having a condenser 84 and tuned to the same 25 frequency as the circuit 71. This circuit 83 is arranged in a lead 85 connected to a plate electrode 86 of the detector 64. Thus the circuits 75 and 83 operating in conjunction with the detector 64 and the circuits 70 and 30 71 have a well understood regenerative action. The detector 64 is arranged to control two circuits 90 and 91 having a common battery 92 and including respectively two telephone receivers 93 and 94, the former being connected to the circuit 75 and the latter to the circuit 83.

In the operation of the system of the present invention, it will be apparent that it is possible to receive simultaneously the 45 high frequency carrier wave and the two secondary, impressed frequencies, the former passing through both branches 60 and 61. The latter with their respective audio-frequency modulations are selected through the 50 action of the oscillatory circuits 70 and 71 respectively and the regenerative circuits 75 and 83. Since the reception of the signals or messages takes place by listening to the amplitude changes of the two secondary frequencies, it is obvious that the receiving 55 operator at the telephone 93 will hear the speech of one transmitting operator impressed upon one secondary frequency while the receiving operator at the telephone 94 will hear the speech of another transmitting operator impressed upon the other secondary frequency. The system is therefore arranged to simultaneously receive two or 60 more messages at one time through a detector 65 arranged for common control.

Having thus fully described my invention, what I claim is:

1. A system for receiving radiant energy in the form of a series of oscillations having a predetermined high frequency and having impressed thereon a plurality of series of secondary oscillations of frequencies differing from each other and from said high frequency, each of said series of secondary oscillations having impressed thereon amplitude variations of audible frequency, comprising a circuit responsive to said first-mentioned frequency, a single wave-responsive device controlled by said first mentioned circuit and having a corresponding plurality of input and output circuits, each of said output circuits being selectively responsive to one of said second-named frequencies, and means included in each of said output circuits for reproducing 85 said waves.

2. A system for the reception of radiant energy in the form of a series of oscillations having a predetermined high frequency and modified in accordance with a plurality of series of secondary oscillations of frequencies differing from each other and from said high frequency, the series of secondary oscillations having impressed thereon amplitude variations in accordance with a plurality of series of sound waves respectively, comprising a circuit responsive to said first-mentioned frequency, a single wave-responsive device controlled by said first mentioned circuit and having a corresponding plurality of input and output circuits, each of said output circuits being selectively responsive to one of said second-named frequencies, and means included in each of said output circuits for reproducing the sound waves. 105

3. A system for receiving radiant energy in the form of high frequency oscillations having impressed thereon a plurality of series of waves of different frequencies, each modulated in accordance with a series of waves of audible frequency comprising a circuit responsive to said first-mentioned frequency, a single electron-emitting device controlled by said first-mentioned circuit and having a corresponding plurality of input and output circuits, said output circuits being selectively responsive to currents of different frequencies corresponding respectively to said second-named frequencies, and means included in each of said output circuits for reproducing the respective series of waves of audible frequency. 110

4. Apparatus for receiving relatively high frequency oscillations modified by a plurality of series of periodic variations of lower frequencies, differing from each other and each having impressed thereon amplitude variations, comprising a circuit responsive to said first-named frequency, a single wave-responsive device controlled by said 125

- first mentioned circuit and having a corresponding plurality of input and output circuits, each of said input circuits being tuned to respond to a different frequency, and to each of the output circuits being tuned to respond to the frequency for which its respective input circuit is tuned and means included in each of said output circuits for reproducing the impressed amplitude variations.
5. A system for signaling including means for producing relatively high frequency oscillations, means for modulating said oscillations comprising a plurality of sources of alternating current of lower frequencies differing from each other, means for independently impressing amplitude variations on each of said alternating currents, means for receiving said oscillations including a circuit responsive to said first-named frequency, a single wave-responsive device controlled by said first-mentioned circuit and having a corresponding plurality of input and output circuits, each of said input circuits being tuned to respond to a frequency corresponding to one of said second-named frequencies, and each of the output circuits being tuned to respond to the frequency for which its respective input circuit is tuned, and means included in each of said output circuits for reproducing the impressed amplitude variations.
6. A system for signaling including means for producing relatively high frequency oscillations, means for modulating said oscillations comprising a plurality of sources of alternating current of lower frequencies differing from each other, means for independently impressing amplitude variations of audible frequencies on each of said alternating currents, means for receiving said oscillations including a circuit responsive to said first-named frequency, a single wave-responsive device controlled by said first-mentioned circuit and having a corresponding plurality of input and output circuits, said input circuits being tuned to respond to different frequencies, and each of the output circuits being tuned to respond to the frequency for which its respective input circuit is tuned, and means included in each of said output circuits for reproducing the impressed, audible, amplitude variations.
7. A system for signaling including means for producing relatively high frequency oscillations, means for modulating said oscillations comprising a plurality of sources of alternating current of lower frequencies differing from each other, means for independently impressing amplitude variations on each of said alternating currents, means for receiving said oscillations including a circuit responsive to said first-named frequency, a single wave responsive device controlled by said first mentioned circuit and having a corresponding plurality of input and output circuits, said input circuits being tuned to respond to different frequencies, and each of the output circuits being tuned to respond to the frequency for which its respective input circuit is tuned, and means included in each of said output circuits for reproducing the impressed amplitude variations.
8. A system for the transmission of energy comprising means for transmitting radiant energy in such a form as to include a plurality of series of periodic variations having different frequencies respectively, and means for receiving said energy including a wave-responsive device having a corresponding plurality of input and output circuits, said input circuits being tuned to respond to different frequencies, and each of the output circuits being tuned to respond to the frequency for which its respective input circuit is tuned, and means included in each of said output circuits for reproducing the impressed amplitude variations.
9. Apparatus for receiving radiant energy of such a form as to include a plurality of series of periodic variations having different frequencies respectively, comprising means for receiving said energy including a wave-responsive device having a corresponding plurality of input and output circuits, each of said output circuits being selectively responsive to a frequency corresponding to one of the series of periodic variations and including an indicating device.
10. A system for receiving radiant energy in the form of high frequency oscillations having impressed thereon a series of periodic variations of lower frequency, comprising a detector having input and output circuits, a closed, oscillatory circuit connected in the input circuit of the detector and tuned to the frequency of the high frequency oscillations, and a second, closed oscillatory circuit connected in the input circuit of the detector and tuned to the frequency of said periodic variations.
11. A system for receiving radiant energy in the form of high frequency oscillations having impressed thereon a series of periodic variations of lower frequency, comprising a detector having input and output circuits and closed, oscillatory circuits connected in said input and output circuits respectively, said closed, oscillatory circuits being regeneratively coupled together and being tuned to the frequency of said periodic variations.
12. A system for receiving radiant energy comprising a vacuum tube detector and a plurality of pairs of circuits connected therewith, each pair including a grid-filament circuit and a plate-filament circuit, tuning elements connected with both the grid-filament circuit and the plate-filament circuit of one pair of circuits to render such pair of

circuits responsive to energy of a predetermined frequency and tuning elements connected with the grid-filament circuit and plate-filament circuit of another pair of circuits and having different electrical constants from said first-mentioned tuning elements to cause said pairs of circuits to re-

spond to energy of different frequencies respectively.

Signed at New York in the county of New York and State of New York this 12th day of May 1920.
